ATTORNEY.

UNITED STATES PATENT OFFICE.

ARTHUR E. CHASE, OF TOLEDO, OHIO, ASSIGNOR TO GRAND COUNCIL OF THE LADIES' ORIENTAL SHRINE OF NORTH AMERICA, OF WHEELING, WEST VIRGINIA, AN ASSOCIATION.

DESIGN FOR AN EMBLEM, BADGE, OR BUTTON.

61,151.

Specification for Design.

Patented July 4, 1922.

Application filed March 4, 1922. Serial No. 1,046. Term of patent 14 years.

To all whom it may concern:

Be it known that I, ARTHUR E. CHASE, a citizen of the United States of America, and resident of Toledo, county of Lucas, and State of Ohio, have invented a new, original, and ornamental Design for an Emblem, Badge, or Button, of which the following is a specification, reference being had to the accompanying drawings, in which—

The figure is a front elevation of an emblem, badge or button, showing my new design.

I claim:

The ornamental design for an emblem, badge, or button, as shown.

Signed at Toledo, Ohio, this 2nd day of March, 1922.

ARTHUR E. CHASE.

Witnesses:

HAZEL McCOWIE,
W. H. PORTER.
